UNITED STATES PATENT OFFICE.

WALTER J. BARRON, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

979,731.

Specification of Letters Patent. Patented Dec. 27, 1910.

Application filed September 30, 1909. Serial No. 520,327.

To all whom it may concern:

Be it known that I, WALTER J. BARRON, citizen of the United States, and resident of the borough of Brooklyn, city of New York, in the county of Kings and State of New York, have invented certain new and useful Improvements in Type-Writing Machines, of which the following is a specification.

My invention relates to typewriting machines and more particularly to means for returning the printing instrumentalities to normal position.

A common difficulty encountered in typewriting machines is to have the type bars or their actuating means stick in their movements from the printing position, the restoring springs being at times insufficient to return the parts to normal position when the type bars stick. This so-called "sticking" of the type bars in some instances is due to the type bars colliding or jamming together as one type bar on its way to the printing point meets another one returning to normal position. In some instances the type bars stick in the type guide and in other cases the bearings for the type bars are so snug that the bars will not move with sufficient freedom to prevent them from sticking occasionally and to prevent them from returning to normal position in the operation of the machine. It is essential that the bearings be sufficiently snug to preserve alignment and it is often difficult to preserve alignment and yet render the movements of the bars sufficiently free in their bearings to enable them to return from normal position with sufficient freedom. Ordinarily the operator has to take hold of the sticking bar or bars and move them by hand back to normal position. This results in the loss of much time and in soiling the hands of the operator.

The object of my invention generally stated is to overcome certain of the disadvantages pointed out above and to provide simple and efficient means by which the sticking bars or type carriers and their actuating means may be readily restored to normal position.

To the above and other ends which will hereinafter appear, my invention consists in the features of construction, arrangements of parts and combinations of devices to be hereinafter described and particularly pointed out in the appended claims.

In the accompanying drawings wherein like reference characters indicate corresponding parts in the various views, Figure 1 is a vertical, front to rear, sectional view of sufficient number of parts of one form of typewriting machine to show my invention in its embodiment therein. Fig. 2 is a vertical, transverse, sectional view of the same taken on the line $v-v$ of Fig. 1 and looking in the direction of the arrow at said line. Fig. 3 is a diagrammatic side elevation of sufficient number of parts of a Yost visible machine to show another form of my invention in its embodiment therein. Fig. 4 is a fragmentary front elevation showing some of the parts illustrated in Fig. 3. Fig. 5 is an enlarged detail fragmentary side view partly in section of the type carrying end of a type bar used in the construction shown in Figs. 3 and 4. Fig. 6 is a detail face view of the type-block carrying-spring shown in Figs. 3 and 5.

While I have shown my invention in the present instance embodied in two different forms of front-strike machines, it should be understood that the invention may be employed in various styles of machines.

Referring first more particularly to Figs. 1 and 2, it will be seen that the frame of the machine comprises a base 1, corner posts 2 and a top plate 3. A carriage (not shown) supports a cylindrical rotative platen 4 that is adapted to travel across the top plate from side to side of the machine. A series of segmentally arranged upwardly and rearwardly striking type bars 5 are mounted on type bar hangers 6 secured to a type bar segment 7. The type bars are actuated by pull links 8 connected at their forward ends to angular levers 9 pivoted at 10 to hangers 11 detachably fixed to a supporting segment 11. The forwardly extending arm of each angular lever 9 is connected to a pull link 12 which is inclined downwardly and forwardly where it makes connection at 13 with an upwardly extending arm 14 of a key lever 15. The key levers are fulcrumed on a plate 16 secured to the base of the machine by screws 17. The key levers are provided with the usual finger keys 18 by which the type actions are operated. The parts of each type action are ordinarily restored to normal position by a restoring spring 18^a and by the force of gravity. At times, however, the type bars will, for various reasons hereinbe-

fore stated, be prevented from being restored to normal position by the ordinary means employed for that purpose.

It is the object of the present invention to provide auxiliary positively acting means for restoring the type bars and their actuating means to normal position. To this end I have provided in the construction shown in Figs. 1 and 2, a rock shaft 19 which is mounted in bearing openings in the side plates of the base 1 and one end of said rock shaft projects beyond the side of the machine where it is provided with an arm or finger piece 20 secured at its hub to the rock shaft by a set screw 21. Depending arms 22 are provided with sleeves 23 which surround the rock shaft and are connected thereto by set screws 24. The sleeves 23 bear at their outer ends against the inner sides of the base and thus prevent a longitudinal movement of the rock shaft in its bearing openings. The rock shaft 19 is arranged above the key levers 15 and the arms 22 are situated at the sides of the system of key levers and extend below the same, where they are connected by a cross bar or retractor 25 which extends beneath the key levers. A stop pin 26 extends from one side of the machine into the path of the arm or finger piece 20 in order to limit the rearward movement of said arm.

From an inspection of Fig. 1 it will be seen that the arms 22 extend downwardly and rearwardly from the rock shaft 19 and the weight of the arms and the cross bar 25 may be employed to normally maintain the cross bar 25 in the position shown in Fig. 2. If desired a suitable spring may be employed to effect the movement of the bar 25 and the parts connected therewith to normal position. If a type bar or any of its actuating connections should stick to prevent the return of the parts to normal position by the restoring springs 18, then a forward pull on the finger piece 20 would be effective to elevate the bar 25, thus forcing the depressed key lever or levers upwardly. It will be seen that the construction and arrangement of the parts of each type action is such that an upward movement effected by the bar 25 on the key lever is effective to restore the key lever and the parts controlled thereby to normal position. It will also be seen that the bar 25 is effective to cooperate with any or all of the key levers which may be maintained depressed by the sticking of the parts before the type bars are restored to normal position, and that although this bar 25 and the means for controlling it are independent of the type actions, the bar nevertheless cooperates with the type actions and is operable at will to restore any of them to normal position in the event of any of the parts of a type action sticking before its type bar is returned to a

position of rest in the type basket. Moreover, it will be understood that normally the bar 25 is maintained below the normal extent of dip of the key levers and is normally maintained out of a coöperation with the type actions although it is at all times in a position where it may readily be brought into coöperation with the type actions. The use of this device adds nothing to the weight of the type actions and the device is only employed in the event of a type bar, or the actuating means therefor, failing to return to normal position during the ordinary operation of the machine.

So far as I am aware I am the first to have provided means for positively restoring the type carrier to normal position in the event of it sticking before the carrier returns to normal position, and I wish to be understood as claiming such a construction broadly.

I am aware that various modifications may be made without departing from my invention, and that it is unnecessary to have the restoring means act on the actuating means for the type carrier. If desired, it may act directly on the type carrier.

In Figs. 3 to 6 inclusive I have shown a modified form of construction in which the retractor, or the device whereby the type actions are restored to normal position, co-act directly with the type bars. In this construction I have illustrated the invention embodied in a Yost visible machine, the type action shown in Fig. 3 being essentially the same as that embodied in said machine except for the manner of carrying the type block. In this construction the key levers 27 are pivoted at 28 to the frame of the machine and are each connected by a link 29 with an angular lever 30 which in turn is connected to the forward end of a pull link 31 connected at its rear end with a driver 32 pivoted at 33 to a hanger which is secured to a type bar segment 34. The driver 32 is pivoted at 35 to the type bar proper 36 which has one end thereof pivoted at 37 to one end of a guide link 38, the opposite end of said guide link being pivoted at 39 to a fixed part of the machine. The driver 32 extends beyond this pivot and at the last portion of the printing stroke cooperates with the type bar proper as shown in Fig. 3. An ink pad 40 is supported by the type bar segment and the type faces 41 normally rest against this pad, it being understood that Fig. 3 illustrates the type bar in printing position. The free end of each type bar has a hole 42 extending therethrough to receive the stem 43 of a type block 44. A leaf spring 45 is secured at 46 to the type bar proper and is connected at its free end by a rivet 47 or otherwise with the stem 43 of the type block on the opposite side of the type bar from that at which the type block 48

is situated. The pressure of this spring is normally exerted to maintain the type block in a position such as that indicated in Fig. 5. It will be understood that the type bars 5 of the system are segmentally arranged and strike upwardly and rearwardly against the front face of the platen 4. As the type bar approaches the printing position its type block is received in a fixed type guide 48 secured to the top plate 3 of the machine. The retractor comprises an arm 49 mounted on a rock shaft 50 adapted to turn in bearings 51 and 52 secured to the top plate of the machine. The outer end of the rock 10 shaft is provided with an arm 53 which extends forwardly to the front part of the machine and terminates in a finger piece 54. The arm 53 is secured to the rock shaft 50 by a pin 55 or by any other suitable means. A coiled spring 56 surrounds the rock shaft near the outer end thereof and is connected at one end to the arm 53 and at its opposite end to the fixed bearing 52. This spring exerts a pressure to normally maintain the 15 arms 53 and 49 in the position shown in Fig. 3. The arm 53 is situated directly in front of the fixed type guide 48 and is recessed at its upper end as indicated at 57, the recess registering with the opening 58 in the type guide. A segmental buffer 59 of felt, leather or other suitable material is secured to the front face of the arm 49 so that it is interposed in the path of each of the type bars as they approach the printing position. 20 The relation of the parts is such that the free end portion of the type bar proper 36 will contact with the buffer 59 before a type face on the bar reaches the platen or the paper thereon. The momentum of the parts, however, is sufficient to cause the type block and its stem to move independently of the type bar after the latter is arrested, the movement of the block being effected against the pressure of the spring 45 which connects 25 the type block with the type bar. This independent movement or overthrow of the type block carries a type face on the block against the work sheet and effects an imprint, the spring 45 and the force of the blow against the platen, withdrawing the type face from contact with the work sheet as soon as the imprint has been effected. The arm 49 at this time bears against the fixed type guide to arrest the rearward movement 30 of the arm 49 and thus resists or limits the printing movement of the type bar. The type guide therefore constitutes a stop which limits the movement of the arm 49 and the parts connected thereto to normal position, the spring 56 holding the parts normally in this position. Should the type bar stick in the type guide it is merely necessary to depress the finger piece 54 and this movement 35 effects a forward movement of the arm 49 through the interposed rock shaft 50 which

results in the upper end of the type bar 36 being forced forwardly to disengage the type block from the type guide. This return movement of the bar 36 causes a corresponding return movement of the parts for actuating the type bar. A restoring spring 60 is connected at one end to the link 31 and at its opposite end to the driver 32, this restoring spring being effective ordinarily to restore the parts to normal position. An actuation of the retractor through the finger piece 54 is necessary only where the restoring spring 60 is ineffective to disengage the type block from its guide or to return the parts to normal position. The buffer 59 and the arm 49 which carries it, in addition to forming a part of the retractor, constitute means for arresting the type bars before the types reach the platen as hereinbefore pointed out so that the imprint is effected by an overthrow of the type block. This means enables the type faces to be quickly withdrawn from the face of the platen, or the work sheet thereon, to prevent double imprints or "ghosts" being produced. Moreover, the construction is such that a practically noiseless type action is provided and one in which a substantially uniform imprint is effected at all times, irrespective of the force applied to the printing keys. 40

It will be understood that in both forms of the construction shown I have provided mechanical means auxiliary to and separate from the type action for restoring the type bars to normal position; that said means are out of operation during the printing movements of each of the type actions; and that said means are nevertheless operable at will independently of printing operations to positively restore each type bar, and the parts by which it is actuated, to normal position, in the event of the failure of the ordinary means such as the restoring springs 18^a and 60 to effect such result. 45

Features of the construction disclosed in Figs. 3 to 6 inclusive which are not specifically claimed herein will be made the subject-matter of a separate application. 50

What I claim as new and desire to secure by Letters Patent, is:—

1. In a typewriting machine, the combination of a type action, including a type carrier, the usual means whereby the type carrier is restored to normal position after each printing operation, and means for actuating said type carrier; and auxiliary mechanical means operable at will independently of printing operations to return the type carrier to normal position in the event of it sticking before it is restored to normal position by the usual means employed for this purpose. 55

2. In a typewriting machine, the combination of a type action including a type carrier, the usual means whereby the type car- 60

rier is restored to normal position after each printing operation, and key actuated means for actuating said type carrier; and auxiliary mechanical means operable at will to return the type carrier and its actuating means to normal position in the event of the parts sticking before they are restored to normal position by the usual means employed for this purpose.

10 3. In a typewriting machine, the combination of a series of type actions including a series of type carriers and the usual means whereby each of said carriers is restored to normal position after each printing operation; and auxiliary mechanical means operable independently of printing operations to return to normal position any of said type carriers which may stick before it is restored to normal position by the usual means employed for this purpose.

4. In a typewriting machine, the combination of a series of type actions including a series of type carriers and the usual means whereby each of said carriers is restored to normal position after each printing operation; and auxiliary mechanical means operable at will independently of printing operations to return to normal position all of said type carriers which may stick before they are restored to normal position by the usual means employed for this purpose.

5. In a typewriting machine, the combination of a series of type actions including a series of type carriers, and the usual means whereby each of said carriers is restored to normal position after each printing operation, key actuated means for operating said type carriers; and positively acting auxiliary mechanical means operable at will to return any of said type carriers and its actuating connections to normal position which may stick before the type carrier is restored to normal position by the usual means employed for this purpose.

15 6. In a typewriting machine, the combination of a type, a key, intermediate connections between said key and type, and hand actuated positively acting auxiliary mechanical means operable at will on said connections to restore them and the type bar to normal position in the event of the parts failing to be restored to normal position in the actuation thereof.

7. In a typewriting machine, the combination of a series of types, a series of finger keys, intermediate connections between each finger key and its type, a series of restoring springs, and means independent of said restoring springs and operable at will on said connections of any type to restore said connections and the type to normal position in the event of the parts failing to be restored to normal position in the actuation thereof.

8. The combination with a type action, of

auxiliary mechanical means separate from the type action and under separate key control for restoring the parts of the type action to normal position in the event of the parts failing to be restored to such position by the ordinary means employed for that purpose.

9. The combination with a type action, of mechanical positively acting means separate from the type action and operative at will thereon to move the parts of the type action back to normal position in the event of them sticking before the parts are restored to normal position by the ordinary means employed for that purpose.

10. The combination with a series of type actions, of mechanical means separate from but coöperative at will with all of said type actions to move back to normal position any or all type actions which may happen to stick in the operated position, said means being out of operation during printing operations.

11. In a typewriting machine, the combination of a series of types, a series of key actuated members for actuating said types, and a hand actuated bar coöperative with said key actuated members to positively move them back to normal position.

12. In a typewriting machine, the combination of a series of type bars, a series of key levers, intermediate actuating connections between said type bars and key levers, a release bar coöperative with said key levers, and hand actuated means for actuating said release bar to positively move the key levers back to normal position.

13. In a typewriting machine, the combination of a series of type bars, a series of key levers, intermediate actuating connections between said type bars and key levers, a release bar pivoted to swing beneath the key levers and coöperative with the key levers to move them to normal position, and hand actuated means for swinging said release bar.

14. In a typewriting machine, the combination of a series of type bars, a series of key levers, intermediate actuating connections between said type bars and key levers, a release bar coöperative with said key levers, a rock shaft which carries said release bar, and a finger piece connected to said rock shaft to turn it and thus restore the key levers to normal position.

15. In a typewriting machine, the combination of a type bar, a key lever, a restoring spring, intermediate connections between said key lever and type bar, said connections being such that a downward movement on the key lever moves the type bar to the printing position and an upward movement on the key lever moves the type bar to normal position, and hand actuated means separate from the key lever and restoring spring and

operable at will to move the key lever upwardly and thus restore it and the parts controlled thereby to operative position.

16. In a typewriting machine, the combination of a series of type bars, a series of key levers, intermediate connections between said key levers and type bars, said connections being such that a downward movement on a key lever moves the associated type bar to the printing position and an upward movement on a key lever moves the associated type bar to normal position, and a hand ac-

tuated bar separate from the key levers and operable at will to move the key levers upwardly and thus restore them and the parts controlled thereby to operative position. 15

Signed at Hingham in the county of Plymouth and State of Mass. this 28th day of Sept. A. D. 1909.
